DANCING FIGURE TOY

Edward Briggs, Ames, Iowa

Application March 8, 1948, Serial No. 13,620

2 Claims. (Cl. 46—107)

1

This invention relates to a dancing figure toy and more particularly to a device of this kind of a wheeled type.

It is an object of the invention to provide a toy wherein a manikin having freely movable arms and legs is mounted upon a portable body together with a swinging platform position below the manikin and supported for intermittent contact from below with the manikin when the device is in transit over a support surface to cause the manikin to simulate a clog dance.

It is also an object of the invention to provide a toy wherein is embodied a portable body provided with an upstanding post to support a manikin above and free of contact with the body together with a swinging platform position between the body and manikin and through which the post freely extends and wherein the platform is intermediately moved into contact with manikin when the body is in transit over a supporting surface.

The invention consists in the details of construction and in the combination and arrangement of the several parts of my improved dancing figure toy whereby certain advantages are attained, as will be hereinafter more fully set forth.

In order that my invention may be better understood, I will now proceed to describe the same with reference to the accompanying drawings, wherein:

Figure 1 is a view partly in side elevation and partly in vertical section illustrating a toy embodying the invention;

Figure 2 is a sectional view on the line 2—2 of Figure 1 looking in the direction of the arrows; and

Figure 3 is a view in front elevation.

In the embodiment of the invention as illustrated in the accompanying drawings, B denotes an elongated and relatively wide body member of the desired dimensions and which has its forward end portion bifurcated, as at 1, to provide the forwardly directed side arms 2.

Secured to the outer faces of the arms 2 at the free extremities thereof are the depending flat bearing elements 3, possessing a certain degree of inherent resiliency. The lower portions of these elements 3 freely receive the extremities of the axle 4 for the rotatable member R. The lower portions of the elements 3 can be readily sprung outward sufficiently to effect the desired mounting of the axle 4.

The member R comprises the two substantially duplicate side wheels 5 of preferred radii and between which is arranged a substantially ellip-

tical cam member 6 extending radially across the wheels 5 and of a length substantially equal to the diameter of each of the wheels 5. The longitudinal faces a are arcuate from end to end and preferably on corresponding radii.

The rear portion of the body member B is provided with the upstanding spaced lugs 7 between which is pivotally held as at 8, an end portion of a forwardly directed arm 9 having its free forward end portion underlying and secured attached to a marginal portion of a platform P.

As shown in the drawings, the platform P is circular in plan and of a diameter to extend beyond the outer ends of the arms 2.

15 The central portion of the platform P has an opening 10 through which extends an elongated upstanding post or rod 11 carried by the body member B at its forward end portion.

At a point substantially midway of the arms 20 2, the platform has depending therefrom an arm 12 which carries the downwardly disposed spaced spring bearing plates 14 between which is rotatably supported, as at 15, a wheel 16, which has rolling contact with the longitudinal arcuate faces a of the cam member 6 as the member R rotates during the transit of the device. The contact of the wheel 16 with the faces a of the cam member 6 is maintained by gravity.

When the device is in transit over a supporting surface, the platform P is caused to intermittently swing upwardly and to drop under the action of the cam member 6.

35 Freely engageable with the upper portion of the post or rod 11 is the body 17 of a manikin M of preferred type. The body 17 has extending therein from below and at substantially the axial center thereof an elongated socket 18. The upper extremity of the post or rod 11 is preferably pointed as at 19 for contacting with the inner or closed end of the socket 18 to facilitate turning movement of the body 17 around the post or rod 11.

40 Dangling from the lower portion of the body 17 are the articulated leg members L between which the post or rod 11 is positioned.

45 Pivotedly connected to each side of the body 17 at the upper portion thereof, as at 20, is an end portion of an arm member 21. These members 21 are substantially in duplicate and in the general form of a reversed L and are unbroken from end to end.

50 When the platform P is at the limit of its downward movement, it is substantially parallel with the top of the body member B and when in such position the platform P is spaced from and

below the manikin M on the post or rod 11. However, as the platform P is thrown upwardly by the cam member 6, the leg members L are forcibly struck from below causing the leg members L to swing in an erratic manner and at the same time sufficiently vibrating the body 17 to effect swinging movement of the arm members 21. The action of the platform in striking the leg members L also causes the body member to have rotating action on the rod or post 11 whereby the action of the manikin M is further increased together with increased attractiveness of the toy to the child.

In the present embodiment of the invention, the device is of a push type and has extending upwardly and rearwardly thereof, a rigid push handle member 23 of desired length. As herein comprised, the handle member 23 is carried by and rigid with a depending prop 24 carried by the rear portion of the body member. When the device is at rest, the prop 24 contacts the supporting surface to maintain the device in an upright position.

From the foregoing description it is thought to be obvious that a dancing figure toy constructed in accordance with my invention is particularly well adapted for use by reason of the convenience and facility with which it may be assembled and operated.

I claim:

1. A wheeled toy comprising a horizontal body, a pair of bearing elements extending downwardly therefrom in spaced relation, a rotary unit comprising two wheels and an intermediate member between and coupling the wheels together and an axle extending at its ends beyond the outer sides of the wheels, the unit being between said bearing elements and having the axle ends rotatably connected with such elements, said intermediate member having two opposite, outwardly bowed 40

intersecting faces, a platform above and pivoted on the body for vertical swinging, a manikin supported above the platform and having free moving legs adapted to be struck by the platform upon up and down movement of the latter, an arm carried by the platform and extending downwardly over the turning axis of said unit, and a roller upon the lower end of the arm having rolling contact with said outwardly bowed faces.

2. A wheeled toy comprising a long flat body member having a slot in one end edge, a pair of upstanding ears adjacent to the opposite end thereof, an arm having one end pivotally mounted between said ears for vertical swinging, a pair of spaced bearings extending downwardly from the body adjacent to the said one end edge, a pair of wheels rotatably supported between said bearings, a platform upon the arm and having a portion overlying said slot, a manikin supported above the platform and having articulated legs spaced from the platform to be struck upon up and down movement of the platform, an arm rigidly secured at one end to the platform and extending down therefrom through said slot, said last arm being in line with and perpendicular to the turning axis of the wheels, a cam body supported between said wheels to turn therewith, and a contact element carried upon the lower end of the last named arm and engaging said cam body.

EDWARD BRIGGS.
